UNITED STATES PATENT OFFICE.

STEPHEN V. DILLON, OF TULSA, OKLAHOMA.

AUTOMATIC CATCHING DEVICE FOR WELL TUBING.

Application filed February 8, 1926. Serial No. 86,846.

This invention relates to a device that is adapted to be used for catching a well tubing and preventing said tubing from dropping downwardly into the well in the event 5 the tubing separates or becomes detached from its supporting means, due to breakage or to any other cause.

One object of my invention is to provide a catching device for well tubing that is automatic in its action both when the device is being introduced into the well and after it has been set, and which is of such design that the parts of same are not liable to break or to be rendered inoperative by corrosion or 15 the accumulation of wax or other foreign matter on said parts.

Another object is to provide an automatic catching device for well tubing which is of such design that it overcomes the necessity of arranging a string of pipe below the perforated strainer through which the liquid enters the tubing in instances where the strainer is located a considerable distance above the bottom of the well.

25 Another object is to provide a catching device for well tubing which is of such design that after it has been set it will not produce wear on the tubing or on the well casing, notwithstanding the fact that the jaws are 30 there in engagement with the casing, but nevertheless, will permit the tubing to move longitudinally slightly. In the event of an accident, a collar or abutment on the tubing will strike against a member that causes the 35 pressure of the jaws or gripping members on the well casing to be increased sufficiently to insure the device effectively catching and holding the tubing.

Another object is to provide a catching device for well tubing which is so constructed 40 and arranged that after it has been set, the tubing can be easily raised or lowered to vary the position of the strainer or perforated pipe on the tubing without disengaging the gripping jaws from the casing or side wall of the well.

And still another object of my invention 45 is to provide a catching device for well tubing that is operative at all times to automatically catch the tubing and prevent it 50 from dropping into the well, both when the device is being introduced into the well and after it has been set; but which is of such design that it can be easily installed or removed. Other objects and desirable fea-

tures of my invention will be hereinafter pointed out.

To this end I have devised a catcher or catching device for well tubing that is adapted to be arranged at the lower end of 60 the well and which is provided with jaws or gripping members which are so constructed and arranged that a sudden drop of the tubing during the operation of introducing the device into the well, causes said jaws 65 or gripping members to be automatically wedged tightly enough against the well casing to sustain the weight of the tubing, and after the device has been set the jaws of same grip the casing tightly and are so arranged that the pressure of same on the casing will be increased automatically in the event the tubing starts to drop. The device is inexpensive to construct; it is easy to install or remove; it is of sufficiently rugged 70 construction to insure its remaining in operative condition at all times, and as the device overcomes the necessity of arranging a string of pipe below the strainer, it eliminates many objections and problems that result from the use of a string of pipe below 75 the strainer of a well tubing.

Figure 1 of the drawings is a side elevational view, partly in vertical section, of a catcher or catching device for well tubing 80 constructed in accordance with my invention, illustrating the method of arranging the device in operative position in the casing of the well.

Figure 2 is a similar view, showing the device arranged in operative engagement with the well casing and in readiness to catch the tubing and arrest the downward movement of same in the event the tubing separates or becomes disconnected from its, sustaining 90 means.

Figure 3 is a horizontal cross sectional view, taken on the line 3-3 of Figure 1, looking in the direction indicated by the arrows; and

Figure 4 is a horizontal cross sectional view, taken on the line 4-4 of Figure 2, looking in the direction indicated by the arrows.

Referring to the drawings which illustrate the preferred form of my invention, A designates the casing of a well and B designates the well tubing through which the liquid produced in the well is forced up to the surface of the ground by a conventional pump 105 110.

(not shown). My improved catcher consists of a device which is adapted to be combined with the tubing B and arranged inside of the casing A adjacent the lower end 5 of the well. It comprises a tubular guide member 1 that forms one section of the well tubing and which is connected at its upper and lower ends to the adjacent sections of the tubing by means of coupling collars 2 and 3, a plurality of serrated jaws or gripping members 4 that are adapted to engage the inside of the well casing A, and a wedge-shaped actuating member 5 loosely mounted on the tubular guide 1 and adapted to move 10 longitudinally relatively to said guide so as to cause the gripping jaws 4 to be wedged tightly against the well casing. The jaws 4 are connected by means of links 6 or other suitable devices with a loose collar 7 that surrounds the tubular guide 1, and a supporting member 8 is arranged below the collar 7 so as to sustain the same and cause the gripping jaws 4 to remain at rest relatively to the actuating member 5 during the operation of 20 setting the device. Said supporting member 8 consists of a sleeve that loosely surrounds the tubular guide 1, and said supporting member is provided on its exterior with springs 9 or other suitable friction devices 25 that are adapted to bear against the well casing A and prevent the supporting member 8 from turning with the tubular guide member 1 or moving longitudinally with said guide member, in the operation of setting the device in operative position in the 30 well casing. The tubular guide 1 is provided with two rigid collars 10 and 10^a, both of which are of such diameter that they can move longitudinally through the supporting member 8, and the collar 10^a is provided with laterally-projecting pins 11 which are adapted to be positioned either in engagement with the upper end of the supporting member 8 or in elongated, vertically-disposed slots 12 in the supporting member. In said preferred form of my invention, as herein illustrated, the catcher is provided with four serrated jaws or gripping members 4 arranged symmetrically around the actuating member 5 in sliding engagement with four inclined surfaces or wedges 13 on said actuating member, said wedges having dovetail-shaped, vertically-disposed ribs 14 that fit in correspondingly-shaped grooves in the inner sides of the gripping jaws 4. At the upper end of the actuating member 5 is an integral, externally screw-threaded collar 15 which is adapted to be engaged by a fishing device in the event the threads of the top coupling collar 2 strip.

After the catcher has been combined with the well tubing by means of the coupling collars 2 and 3 at the upper and lower ends of the tubular guide 1, the tubing is moved downwardly into the well, as shown in Fig-

ure 1. At this time the supporting member 8 is inactive and is sustained by the bottom coupling collar 3, the actuating member 5 is sustained by the rigid collar 10 on the tubular guide 1, the loose collar 7 to which the gripping jaws 4 are connected is sustained by the laterally-projecting pins 11 on the rigid collar 10^a, and the pins 11 are in engagement with the upper end of the supporting member 8. The collars 10 and 10^a are disposed in such relation with each other that the gripping jaws 4 will be held out of engagement with the inner side of the well casing A, when the actuating member 5 rests upon the collar 10, and the laterally-projecting pins 11 of the collar 10^a sustain the loose collar 7 and also bear against the upper end of the supporting member 8, thereby permitting the catcher to be moved downwardly through the well 85 casing without causing the gripping jaws to exert undue friction on the casing. If the well tubing should separate or become accidentally disconnected from its sustaining means, during the operation of positioning 90 the catcher in the well, the tubing, actuating member 5 and supporting member 8 would start to move downwardly with greater speed than the parts 4 and 7, which action would result in the gripping jaws 4 being 95 automatically forced outwardly into sufficiently snug engagement with the well casing to cause the actuating member 5 to act as an abutment that arrests the downward movement of the well tubing when the top 100 coupling collar 2 strikes against the upper end of the actuating member 5. This action results from the fact that the well tubing and actuating member 5, being of greater weight than the gripping jaws 4 and collar 7, travel 105 downwardly at a greater speed than said jaws, and thus cause the actuating member 5, which is then sustained by the rigid collar 10, to move longitudinally relatively to the gripping jaws, whereupon the wedges 13 on 110 said actuating member expand the gripping jaws or wedge them tightly against the inner surface of the casing. It will thus be seen that in a well tube catcher of the construction above described there is no danger 115 of the tubing dropping into the well in the event it breaks away from its supporting means during the operation of setting the catcher in the casing, because the catcher is constructed in such a manner that downward 120 movement of the tubing and the actuating member 5 relatively to the gripping jaws causes said jaws to be automatically wedged tightly against the well casing.

Ordinarily the catcher will move downwardly through the well casing with the parts of the catcher occupying the position shown in Figure 1, and after the strainer on the well tubing has reached the desired position, the catcher is actuated in such a 125 130

way as to cause the gripping jaws to be forced into snug engagement with the well casing. This is effected by first rotating the well tubing B slightly so as to arrange 5 the laterally-projecting pins 11 on the collar 10^a in alignment with the upper ends of the elongated slots 12 in the supporting member 8, and then moving the tubing downwardly into the position shown in Figure 2 so as to disengage the collar 10 from the actuating member. When the tubing is rotated, as above described, the supporting member 8 remains at rest, or does not turn with the tubing, due to the frictional engagement 10 of the springs 9 on said supporting member against the inner surface of the well casing and after the pins 11 on the collar 10^a have come into alignment with and start to move downwardly through the 15 elongated slots in the supporting member 8, said supporting member remains at rest, due to the frictional pressure of the springs of same on the interior of the well casing, thereby causing the loose ring 7 and the 20 gripping jaws 4 connected to same to be sustained by the supporting member 8. Accordingly, when the well tubing B is rotated slightly and then moved downwardly, thus carrying the collar 10 on the tubular member 1 out of engagement with the lower end 25 of the actuating member 5, said actuating member will move longitudinally with relation to the gripping jaws 4 and force said jaws tightly against the well casing, the 30 downward movement of the well tubing being stopped after the top coupling collar 2 has reached a position slightly above the upper end of the actuating member 5, as shown in Figure 2. If the tubing should 35 separate or become accidentally disconnected from its sustaining means, after the catcher has been set in its operative position, as shown in Figure 2, the tubing would start to move downwardly, but as soon as the 40 top coupling collar 2 strikes against the upper end of the actuating member 5, the entire weight of the tubing will be exerted on 45 said actuating member in a direction tending to wedge the gripping jaws 4 tightly 50 against the well casing. Consequently, after the catcher has been set in operative position in the well, it is always in readiness to automatically catch the tubing and sustain 55 the weight of same in the event of an accident that results in the tubing separating or becoming accidentally disconnected from the means that normally sustain the tubing in the well. If, after the catcher has been 60 set in operative position in the well, it becomes necessary to raise or lower the tubing slightly, this can be accomplished without disturbing the jaws of the catcher or disconnecting said jaws from the well casing, due to the fact that the tubular guiding member 1 of the device has a loose fit

in the actuating member 5, in the collar 7 and in the supporting member 8, and the top coupling collar 2 and rigid collar 10 on the tubular member 1 are spaced far enough apart to permit of a slight longitudinal movement of the well tubing, without causing said collars 2 and 10 to strike against the ends of the actuating member 5. When the catcher is to be removed from the well, this can be accomplished quickly and 70 easily by raising the well tubing so as to cause the rigid collar 10 on the tubular guide member 1 to strike against the lower end of the actuating member 5 and move it upwardly, thereby releasing the gripping jaws 80 4 from engagement with the inner surface of the well casing.

A well tubing catcher of the construction above described is sufficiently strong and rugged to successfully withstand the rough usage and strains to which such devices are subjected; the parts of same are not apt to be rendered inoperative by corrosion or the accumulation of wax or other foreign matter; it is always in readiness to automatically catch and effectively hold the well tubing, both in the operation of positioning the catcher in the well and after the catcher has been set in the desired position; it will 90 not cause wear on the well casing or on the well tubing; it permits the tubing to be raised or lowered to change the position of the strainer without disturbing the position of the jaws of the catcher, and as it overcomes the necessity of arranging a string of 95 pipe below the perforated strainer of the well tubing, it enables a pumping well to be maintained in operative condition with minimum trouble and expense.

It will be observed that the parts 7 and 8 form tubular means, and that the parts 4, 6 and 7 make up a slip assembly. Furthermore, the sleeve 8 and the friction springs 9 constitute an auxiliary actuating member provided with friction means. In some of the appended claims, these parts will be referred to by such terms.

While I have described the device as being used in a well that is equipped with a casing, it will be obvious that the device is 105 capable of being used with an uncased well, and that when used in this manner, the gripping jaws of the device act directly on the side wall of the well.

Having thus described my invention, what I claim as new and desire to secure by Letters Patent is:

1. A catching device for well tubing, comprising a guide that forms a section of the tubing, an actuating member adapted to move longitudinally of said guide, gripping jaws adapted to be forced against the casing by said actuating member, means on said guide for sustaining said actuating member and jaws during the operation of in

troducing the device into the well, constructed so that a sudden drop of the tubing causes said actuating member to force the jaws against the casing, and an independent means that is inoperative when the device is being introduced into the well, constructed so as to temporarily sustain said jaws and prevent them from moving longitudinally with the actuating member when said actuating member is being operated to set the device.

2. A catching device for well tubing, comprising a guide that forms a section of the well tubing, a tapered actuating member arranged to move longitudinally of said guide, gripping jaws that co-operate with said actuating member, means on said guide for holding said actuating member and jaws in inactive relationship during the operation of introducing the device into the well, constructed so that a sudden drop of the tubing causes the actuating member to force the jaws tightly against the casing, and an independent means adapted to frictionally engage the well casing so as to prevent said jaws from moving longitudinally with said actuating member when said member is being operated to set the device in the well.

3. A catching device for well tubing, comprising gripping jaws, an actuating member arranged so that it is capable of moving longitudinally relatively to the tubing, means carried by the tubing for maintaining said jaws and actuating member in an inactive relationship during the operation of introducing the device into the well, constructed so that a sudden drop of the tubing causes said actuating member to force the jaws tightly against the casing, and an independent means that is inactive during the operation of introducing the device and which is provided with friction elements that co-operate with the casing to effect the gripping of the jaws on the casing during the operation of setting the device.

4. A catching device for well tubing, comprising a guide that forms a section of the tubing, an actuating member adapted to move longitudinally of the guide, gripping jaws that co-operate with said actuating member, means on said guide for holding said jaws and actuating member in an inactive relationship during the operation of introducing the device into the well, constructed so that a sudden drop of the tubing renders said jaws operative, a supporting member on said guide provided with friction elements that are adapted to engage the well casing, and a means for holding said supporting member in an inactive condition during the operation of introducing the device, constructed so that a slight rotary movement of the tubing causes said supporting member to become operative.

5. A catching device for well tubing, com-

prising a guide that forms a section of the tubing, an actuating member adapted to move longitudinally of said guide, gripping jaws that co-operate with said actuating member, a supporting member on said guide provided with friction elements that are adapted to co-operate with the casing to cause the actuating member to force the jaws tightly against the casing during the operation of setting the device, and a means for causing said supporting member to move with the guide during the operation of introducing the device, constructed so that it will be rendered inoperative by a slight rotary movement of the tubing after the device has reached the position in which it is to be set.

6. A catching device for well tubing, consisting of a tubular guide member that forms a section of the well tubing, a pair of spaced stops combined with said guide member, a tapered actuating member loosely mounted on said guide member and adapted to move longitudinally of same, gripping jaws that are adapted to be forced tightly against the well casing or side wall of the well by the longitudinal movement of said actuating member in one direction, and a means carried by said guide for preventing relative longitudinal movement of said gripping jaws and actuating member during the operation of introducing the device into the well, constructed so as to cause said actuating device to move longitudinally and render said jaws operative in the event the tubing starts to drop during the operation of introducing the device into the well.

7. A catching device for well tubing, comprising a tubular guide member that forms a section of the well tubing, spaced stops combined with said member, a tapered actuating member loosely mounted on said guide member and adapted to move longitudinally relatively to same, gripping jaws adapted to be actuated by longitudinal movement of said actuating member in one direction, a rigid collar on the guide member that sustains said actuating member during the operation of introducing the device into the well, a loose collar on said guide member joined to said jaws, and a supporting member below said loose collar sustained by one of said stops during the operation of introducing the device into the well, and provided with elements that are adapted to frictionally engage the casing or side wall of the well during the operation of setting the device.

8. A catching device for well tubing, comprising a tubular guide member that forms a section of the well tubing, spaced stops combined with said member, a tapered actuating member loosely mounted on said guide member and adapted to move longitudinally of same, gripping jaws adapted to

- be actuated by longitudinal movement of said actuating member in one direction, a rigid collar on the guide member that sustains said actuating member during the operation of introducing the device into the well, a loose collar on said guide member joined to said jaws, a supporting member below said loose collar adapted to be sustained by one of said stops during the operation of introducing the device into the well, and provided with elements that are adapted to frictionally engage the casing or side wall of the well during the operation of setting the device, a second rigid collar on said guide member arranged below said loose collar, and a laterally-projecting pin on said second collar for the purpose described.
9. A catching device for well tubing, consisting of a tubular guide member that forms a section of the well tubing, coupling collars arranged at the upper and lower ends of said guide member, a tapered actuating device loosely mounted on said guide member and adapted to move longitudinally of same, serrated gripping jaws arranged on the outside of said actuating member and adapted to be forced tightly against the casing or side wall of the well by longitudinal movement of said actuating member in one direction, a rigid collar on said guide member that sustains said actuating member during the operation of introducing the device into the well, a loose collar on the guide member connected by links to said jaws, a supporting member loosely mounted on the guide member above the bottom coupling collar and provided with elements which are adapted to co-operate with the well casing to hold said supporting member against movement during the operation of setting the device, and a second rigid collar on the guide member provided with a laterally-projecting pin that is adapted to engage the upper end of the supporting member when the device is being introduced and enter an elongated slot in said supporting member and move downwardly through same when the device is being set.
- 50 10. A catching device for well tubing, consisting of a tubular guide member that forms a section of the tubing, coupling collars at the upper and lower ends of said guide member, a tapered actuating member loosely mounted on said guide member and adapted to move longitudinally of the same, gripping jaws arranged in sliding engagement with said actuating member means on said guide member that sustains said actuating member and gripping jaws and prevent relative movement of same during the operation of introducing the device into the well, and an independent supporting means for the gripping jaws that is adapted to temporarily sustain the same during the operation of setting the device and prevent said jaws from moving relatively to the actuating member when said actuating member is moved intentionally in a direction to force said jaws into engagement with the casing or side wall of the well.
11. A catching device for well tubing, consisting of a tubular guide member that forms one section of the well tubing, coupling collars at the upper and lower ends of said member, an actuating device mounted on said guide member so that it can move longitudinally of the same and provided at its upper end with an externally-screw-threaded collar, wedges on said actuating member, serrated gripping jaws combined with said wedges so as to move longitudinally of same, a loose collar on the guide member connected by links with said jaws, a supporting member loosely mounted on the guide member below said loose collar and provided with frictional gripping elements that are adapted to engage the casing or side wall of the well, a rigid collar on said guide member that sustains said actuating member during the operation of introducing the device into the well, a second rigid collar on said guide member provided with laterally-projecting pins that are positioned between said loose collar and the upper end of said supporting member during the operation of introducing the device in the well, and elongated, vertically-disposed slots in said supporting member that are adapted to receive said pins and permit the guide member to move longitudinally of said supporting member when the device is being set in the well so as to cause the actuating member to render the gripping jaws operative.
12. The combination with a well casing and tubing therein, of a tubing catcher slideable axially on the tubing and including an actuating member, a slip assembly and an auxiliary actuating member provided with friction means, said slip assembly including gripping jaws adapted to be forced against the casing by the first mentioned actuating member, the slip assembly being lighter in weight than the first mentioned actuating member and tubing, whereby, during an abrupt drop of the tubing, the first mentioned actuating member will descend at a greater speed than the slip assembly and overtake the gripping jaws to force the same into engagement with the casing, said auxiliary actuating member comprising a sleeve provided with a substantially vertical slot and a substantially horizontal shoulder merging into one wall of the slot, and a pin on the tubing adapted to engage either the shoulder or the slot for either latching the auxiliary actuating member in a fixed position on the tubing, or to permit the tubing to slide axially relatively to the auxiliary member.

13. The combination with a well casing and tubing therein, of a tubing catcher surrounding the tubing and loosely mounted on the latter to permit the tubing to reciprocate while the catcher is anchored in position in the casing, said catcher including tubular means, gripping jaws, a wedge-shaped actuating member and friction means, a part of the tubular means being operatively connected to the gripping jaws, and another part of the tubular means operatively connected to the friction means, said friction means engaging the casing for holding the tubular means and gripping jaws in a fixed position while the wedge-shaped actuating member forces the gripping jaws into engagement with the casing.
14. The combination with a well casing

and tubing therein, of a tubing catcher arranged between the tubing and the casing 20 and adapted to form an abutment to catch the tubing in case of accidental drop of the tubing, said catcher including a wedge-shaped actuating member through which the tubing is axially movable, tubular means 25 through which the tubing is axially movable, resilient means connected to a part of the tubular means and engaging the casing for holding said tubular means in a fixed position in the casing, and gripping jaws 30 operatively connected to the tubular means and engaging the wedge-shaped actuating member, said gripping jaws being held in engagement with the casing by said actuating member.

STEPHEN V. DILLON.
